UNITED STATES PATENT OFFICE.

JOHN JACOB ASTOR, OF NEW YORK, N. Y.

SECURING DEVICE FOR CHAIRS.

961,093.

Specification of Letters Patent. Patented June 14, 1910.

Application filed October 14, 1909. Serial No. 522,548.

To all whom it may concern:

Be it known that I, JOHN JACOB ASTOR, a citizen of the United States, and a resident of the city of New York, borough of 5 Manhattan, in the county and State of New York, have invented a new and Improved Securing Device for Chairs, of which the following is a full, clear, and exact description.

Many people in crossing the ocean have experienced inconvenience by reason of the fact that the chairs in the saloon and card-rooms are rigidly secured to the floor. The chairs are secured at such a distance from 10 the tables that they will accommodate persons of very ample proportions, so that when a comparatively thin person occupies a chair, he finds it necessary to sit merely on the edge, for should he endeavor to lean back 15 in the chair, he finds himself too far from the table.

The object of my invention is to provide means whereby the chair may be firmly secured to the floor at any point desired, or 20 may be readily and quickly released to permit it to be moved about.

My improved holding means includes a suction or vacuum cup supported beneath the chair and adapted to engage with the 25 floor, and provided with suitable means for operating it to make or break the vacuum, to secure or release the chair.

The invention consists in the arrangement and combination of parts hereinafter 30 described and particularly pointed out in the claims.

Reference is to be had to the accompanying drawings, forming a part of this specification, in which similar characters of reference indicate corresponding parts in both 35 the figures, and in which—

Figure 1 is a perspective view of a chair constructed in accordance with my invention; and Fig. 2 is a side elevation of the 40 chair, the vacuum cup and its operating parts being shown in section.

My improved holding means may be used in connection with various different kinds of chairs, as said means does not involve any 45 of the essential features of the chair.

In the accompanying drawings, I have 50 illustrated a chair in which there is a base portion 10 and a revolving seat 11. The seat is suitably upholstered and is provided 55 with a back and arms 12. The base 10 includes a plurality of legs 13, rigidly con-

nected to an upper plate member 14, which latter rotatably supports the chair bottom 11. For holding the legs 13 rigid in respect to each other at their lower ends, there is provided a lower plate member 15, through which each and all of the legs extend. The lower plate member 15 is provided with a central aperture 16 therein, and within which is mounted my improved vacuum cup 60 17. The plate 15 serves to partially conceal the cup, and as the edges of the opening come adjacent the periphery of the cup, the plate serves to additionally hold or limit the movement of the cup after the vacuum 65 is partly lost. The cup is substantially hemi-spherical, with its lower or free edge adapted to engage with the floor, and with means connected to the upper or central portion for operating the cup to make or 70 break the vacuum. This means, as illustrated, includes a vertically-movable rod 18, slidable within the collar 19 of a spider 20, and adapted to move vertically through said collar. The rod is provided with gear teeth 80 in one side thereof, and the spider serves to support a pinion 21, by the rotation of which the rod is raised or lowered. The pinion is mounted on a shaft 22, which extends out from beneath the chair bottom, 85 and is provided with a suitable handle 23, for rotating the same.

To operate my improved device, it is merely necessary to turn the handle 23, so as to lower the rod 18 and depress or flatten the vacuum cup. This forces the air out from beneath the cup, so that when the handle is turned in the reverse direction to raise the cup, a partial vacuum will be created within the cup, and the latter will thus 90 be prevented from sliding about on the floor. With the chair on a deck, hard-wood floor, or rubber tiling, the vacuum will hold for an indefinite time, but it may be broken at any time by a depressing of the cup. With the 95 cup raised out of engagement with the floor, it will not interfere in any way with the free movement of the chair.

The chair is especially designed for use on board ship, where it is necessary that the 100 chairs be normally secured in place to prevent them from sliding about, although it is, of course, evident that the device could be used in various other places where it is desired to detachably secure a chair or other 105 object in position.

Having thus described my invention, I

claim as new and desire to secure by Letters Patent:

1. A chair having a vacuum cup for engagement with the floor, a vertically-movable rod connected to the upper portion of said cup, and a rack and pinion for raising and lowering said rod and cup.

2. A chair having a seat, a plurality of legs, a plate connecting said legs adjacent the floor and having a central aperture, a vacuum cup mounted within said aperture and adapted to engage with the floor, and means for engagement with the upper portion of said cup for raising and lowering the same, to create a partial vacuum therein.

3. A chair having a seat, a plurality of legs, a plate connecting said legs adjacent

the floor and having a central aperture, a vacuum cup mounted within said aperture and adapted to engage with the floor, a rod extending upwardly from said cup and having rack teeth at one side thereof, a pinion in engagement with said teeth, a shaft supporting said pinion, and a handle at the outer end of said pinion for rotating the same.

In testimony whereof I have signed my name to this specification in the presence of two subscribing witnesses.

JOHN JACOB ASTOR.
